PUMP FOR DIESEL ENGINES

William Fels, Foley, Ala., assignor to F-S-K
Manufacturing Company Incorporated, Mobile,
Ala., a corporation of Alabama

Application December 13, 1945, Serial No. 634,660

2 Claims. (Cl. 103—38)

1

The present invention relates to internal combustion engines and more particularly to improvements in the construction and operation of diesel-type engines.

It is a well known fact, that in diesel internal combustion engines the first atomized fuel entering the engine encounters a rich supply of oxygen, but during the latter part of the charge, an increasingly poorer oxygen supply is developed, with the result that the fuel is converted into fine coke particles or smoke and its maximum efficiency is not obtained. To overcome this unfavorable condition and at the same time simplify the construction and operation of a reliable fuel injection assembly, it is an object of the present invention to provide means that may be associated with a single or multi-cylinder diesel engine that will: (1) greatly eliminate unburned fuel and obtain maximum or higher efficiency on increasing loads, (2) completely synchronize the flow of fuel to all of the cylinders in accordance with the load and, (3) simplify construction and reduce operating parts and cost to a minimum.

Another object of the invention consists in associating with a single or multi-cylinder diesel engine, a fuel pump construction provided with means for insuring a uniform distribution and complete combustion so as to obtain maximum power and minimum dissipation of the fuel. An essential feature includes associating with the pump, a movable wedge shaped member operable by the governor of the engine for controlling the flow of the fuel under pressure into and through the pump into a valve injector associated with each of the cylinders of the engine so as to automatically control the flow of fuel in accordance with the engine load.

Another object of the invention consists in providing a fuel pump for delivering variable quantities of fuel to each of the cylinders of the engine as determined by the engine load, and includes mounting in the pump casing a reciprocating plunger, the movement of which in one direction creates a suction to force the fuel into the pump and the movement of the plunger in an opposite direction develops a pressure for discharging the fuel from the pump and delivers the same in select quantities or amount into each of the cylinders. The plunger is operatively connected to a transverse wedge member operable by the governor through a control pin, one end of which is arranged to extend into an opening formed in the pump. A pivoted lever having upper and lower arms is associated with the

2

pump and has its upper arm extending into the opening in the pump to engage the control pin and is yieldably maintained in its normal vertical position. The lower arm of the lever engages a shaft provided with spaced cams, corresponding in number to the number of cylinders of the engine. The parts are constructed and arranged so that the wedge member controls the reciprocating movement of the plunger and the movement of the control pin is regulated by the pivoted lever through its connection with the cam shaft, with the result that when the piston of each cylinder is in its firing position, the proper amount of fuel is conducted to the cylinder in accordance with the engine load, and the remaining injection valves are closed by releasable means operatively associated therewith.

A further object consists in associating with a multiple-cylinder engine and the fuel pump, 20 a plunger valve injector for controlling the flow of atomized fuel to each cylinder of the engine, and providing means in the form of a movable member for moving the injector valve against its seat so as to cut off supply of fuel to the cylinder when the piston thereof is in its non-firing position and to permit movement of the valve injector by the pressure of the fuel when the piston associated with the cylinder is moved to its firing position.

Other objects and advantages of the invention will become apparent from the following description when taken in conjunction with the accompanying claims and drawings.

Referring to the drawings in which are shown 35 preferred embodiments of the invention:

Figure 1 is a side elevation with parts in section of a three-cylinder two-cycle diesel engine showing the novel features of the invention associated therewith.

Figure 2 is an enlarged detailed sectional view 40 of the cylinder head of one of the cylinders showing the plunger valve injector and stop means associated therewith.

Figure 3 is a sectional view taken substantially 45 along the line 3—3 of Figure 2.

Figure 4 is a detailed sectional view of the bracket member on the cylinder head for guiding the control lever, taken substantially on the line 4—4 of Figure 1.

Figure 5 is a sectional view taken substantially 50 along the line 5—5 of Figure 1.

Figure 6 is a sectional view taken substantially along the line 6—6 of Figure 1.

Figure 7 is a sectional view taken substantially 55 along the line 7—7 of Figure 1.

Figure 8 is an enlarged longitudinal sectional view of the fuel pump assembly.

Figure 9 is a plan view of Figure 8 with parts in section for clearness of illustration.

Figure 10 is a detailed sectional view showing the push rod connection between the cam shaft and the control lever of one of the cylinders.

Figure 11 is a side elevation of a single cylinder of a diesel engine with parts in section and showing the same operatively associated with the fuel pump.

Figures 12, 13 and 14 are detail sectional views showing the different positions of the wedge member and its associated parts when the reciprocating plunger is moved from its zero or closed position to its intermediate position, and to its full load position respectively.

Figure 15 is a detailed sectional view of the injector valve plunger moved to its raised position to allow fuel to be introduced into the cylinder and;

Figure 16 is a sectional view taken substantially along the line 16—16 of Figure 15.

In Figure 1, the novel features are shown associated with three cylinders 15, 16 and 17 of a two-cycle diesel engine. The head 18 of each cylinder has an opening 19 in which is mounted the combustion chamber 20 (Figure 2). An injector casing 21 is preferably provided with a tapered bottom portion 22 which engages a complementary tapered surface 23 in the top of the combustion chamber 20. A fuel pump 24 has at one end an enlarged annular recess 25 (Figure 8) that receives a reduced cylinder portion 26 of a fuel supply member or fitting 27 that may be detachably clamped to the pump by the threaded set screw 28. Fuel from a suitable source of supply or tank is conducted under pressure through the pipe 29 into a receiving chamber 30 in the member 27, and the supply of fuel is normally cut off by ball check valve 31 which is urged into engagement with its seat 32 by a coil spring 33. The chamber 30 communicates with a supply chamber 34 through a port 35 and the chamber 34 communicates with an outlet chamber 36 through a port 37. A spring press ball check valve 38 normally acts to close the port 37, and when the ball valve 38 is raised, the fuel under pressure is conducted through the pipe or flexible connection 39 into a branch coupling 40 (Figure 1) that communicates through the pipes 41, 42 and 43 with the injectors 21 in each of the cylinders 15, 16 and 17 respectively.

The fuel pump 24 is provided in the end opposite the annular member 25 with an elongated recess 44 and an intermediate solid portion 45 having an axial bore 46 which receives a sliding control pin or member 47 that has its upper intermediate surface cut out or removed as at 48 to receive a transversely disposed member or lever 49 that extends through a transverse opening 50 in the solid portion 45 of the pump. The left hand side wall of the cut out portion 48 is formed with a straight edge 51 (Figure 9) that engages the adjacent straight side of the member 49, while the opposite side wall is preferably nosed or convexed as at 52. The transverse member 49 is formed with a tapered or inclined side 53 that engages the curved surface 52 when the lever 49 is moved transversely relative to the pump. A governor 54 associated with the engine is operatively connected to the lever 49 through the links 55 and 56 so as to impart longitudinal movement to the member 49 as determined by the load on the engine. The solid portion 45 of

the pump 24 is also provided with a vertical through opening 57 (Figure 8) into which extends the upper arm 58 of a lever 59 that is pivoted as at 60 to the outer side of the cylinder 16. The lower arm 61 of the lever 59 engages the outer surface of a cam shaft 62 that is provided with circumferentially spaced cam surfaces 63, which equal in number the number of cylinders associated with the engine. In the present instance, three cams 63 are provided so as to correspond with the cylinders 15, 16 and 17. The cam shaft 62 may be operated by any suitable means connected to the crank shaft of the engine and as shown is provided with a gear 64 (Figure 1) which meshes with a complementary gear 65 keyed to a longitudinally disposed cam shaft 66, having at one end a gear 62 connected to gear 13 that may be driven by the crankshaft of the engine. Within the recess 44 of the pump 24, is a cup shaped member 67 that engages one end of a pin 68 that extends transversely into the opening 57 and engages at its opposite end a socket 69 in the upper arm 58 of the lever 59 so as normally to urge the arm 58 against the adjacent wall of the opening 57. A coil spring 70 is confined within the recess 44 between the cup 67 and an adjustable plug 71 which is threaded to the outer end of the pump to control the tension of the spring 70. Into the enlarged axially disposed chamber 34 (Figure 8) extends one end of a reciprocating plunger 73 that engages the bottom of closed end 74 of a hollow plunger or slideable guide member 78. A coil spring 75 contacts at one end with the bottom 74 and has its other end extending into a recess of plug 76 that is threaded as of 77 to the inner wall of the chamber 34. The bottom 74 may also be provided with openings 74' which allow the fluid to pass freely into the plunger 78. The plunger 78 with its perforated bottom 74' is loosely mounted in the chamber 34 and functions merely to constitute a guide for the spring 75.

The reciprocating plunger 73 abuts and is in longitudinal alignment with the adjacent end of the control rod 47 and is constantly maintained in engagement therewith by the tension of the spring 75. The opposite end 14 of the control rod 47 is arranged to project into the vertical opening 57 and the distance it moves into this opening is determined by the position of the transverse wedge member 49 that is moved transversely relative to the pump 24 by the load on the engine through the governor 54 or the like. When the load remains constant the slideable wedge member 49 will remain in a fixed position, but if the load varies, it will cause a correspondingly transverse movement of the member 49 relative to the pump, to increase or decrease the supply of fuel to the engine. It will be seen that as the shaft 62 (Figure 8) rotates in a clock-wise direction, the arm 61 will gradually be moved to the right as it passes over a cam 63 and suddenly drops onto the outer surface of the shaft 62. When the arm 61 engages one of the cams 63 the upper arm 58 is moved away from the wall of the opening 57 and when the arm 61 is released from the cam surface, the tension of the spring 70 will rapidly move the arm 58 to its normal or vertical position. Simultaneously with the movement of the lever 59, when operated by one of the cams 63, the control pin 47 and plunger 73 are moved axially to the left (Figure 8) by the tension of the spring 75. The chamber 34 is arranged to be completely filled with oil or other suitable fuel 75 and it will be noted that when the parts are in

the position as shown in Figure 8, an end portion of the plunger 73 extends into the chamber 34. As the spring 75, when the arm 61 of the lever 59 is out of contact with one of the cams 63, causes the plunger 73 to be moved outwardly relative to the chamber 34, this axial movement of the plunger creates a suction in the chamber 34 sufficient to raise the valve 31 so as to fill the chamber 34 with fuel, while the quick return movement of the arm 59 by release of the spring 70, causes the plunger 73 to rapidly force the fuel in the chamber 34 past the outlet valve 38 into each of the cylinders of the engine. The location of the wedge member 49 determines the axial movement of the plunger 73 and the distance the end 14 of the control pin extends into the vertical opening 57. Thus, it will be seen that the position of the slideable wedge member 49 on the control pin 47 will select and control the quantity of fuel delivered to each cylinder as determined by the load, and that the opposed tension of the springs 70 and 75 under control of the lever 59 and cam shaft 62, will act to move the plunger 73 and 78 to draw the fuel slowly into the pump and rapidly therefrom into each of the cylinders. The spaced cams 63 on the shaft 62 are always in the same position relative to the operating direction of the engine, but are automatically released upon a reverse direction of the engine.

The fuel after passing through the pump 24 is conducted by the branch coupling 40 to each of the fuel injectors 21 through the pipes 41, 42 and 43. An externally threaded tubular member 79 (Figure 2) extends into an opening in one side of the injector casing 21 and is connected at its outer end by clamping nut 80 to the adjacent fuel supply pipe. The bottom of each of the injector casings 21 has an atomized chamber 81 (Figure 15) that communicates through the reduced passage 82 with the tubular member 79, and a reduced passage 83 that communicates through the port 84 (Figure 2) with the combustion chamber 20. The upper end of the passage 83 is formed with a conical valve seat 85 arranged to receive a complementary formed valve 86 on a reciprocating injector plunger 87 that extends through a vertical opening 87' in the injector body or casing 21. Each of the injectors 21 is maintained firmly in position relative to its associated combustion chamber by a clamping member 88 (Figure 2). Extending through the clamping member 88 is a tubular member 89 having a reduced threaded portion that extends into a chamber 90 formed in the top of the injector 21. Slidably mounted in the tubular member 89 is a rod 91 having at its lower end a head 92 that engages the upper end of the injector valve 87. A threaded plug 93 is connected as at 94 to the wall of a recess formed in the upper end of the tubular member 89 and has a longitudinal bore 95 through which extends the upper end 96 of the rod 91. A coiled spring 90' confined between the head 92 and the inner end of the plug 93 serves to move the injector valve 86 against its seat 85 but is contracted by the pressure of the fuel into the chamber 81 so as to allow the valve 86 to be moved away from its seat during the firing operation. Positioned above the three rods 91 of the cylinders 15, 16 and 17 are transversely disposed levers 97, 98 and 99. Each of these levers is pivotally connected at one end as at 100 to a bracket 101 that is secured at its lower end by a bolt 102 to the adjacent cylinder of the engine (Figure 1). Each of the levers 97, 98 and

99 at the end opposite to the pivotal connection 100 is connected to a push rod 103 through an externally threaded plug 104 (Figure 10) that extends through a threaded opening 105 in the adjacent lever such as 97, for adjustment purposes, and is locked in adjustment by the nut 106 that bears against the top of the lever. The lower portion of the plug 104 has an elongated flaring recess 107 into which extends the upper end of the push rod 103. The lower end of the push rod fits into a similar recess 108 in a member 109 that is slidably mounted in a bushing 110 positioned in an opening 111 in the engine casing. The lower end of the plug 109 engages a cam surface 112 on the shaft 66. It will be seen from Figure 1 that the cams 112 on the shaft 66 are positioned circumferentially 120° apart so as to control the movement of the injector valve during the movement of the pistons in the respective cylinders to their firing and non-firing positions. An overballast spring 113 is adjustably connected at its upper end through the eye bolt 114 to each of the control levers 97, 98 and 99 and is secured at its lower end to the adjacent cylinder by the eyelet bolt 115. In order to limit the downward movement of each of the control levers about its pivot, the free end portion of each of these levers may extend through a recess 116 formed in a rod 117 that is fastened by a bolt 118 to the cylinder heads.

Each of the injector casings 21 has a return pipe 119 that communicates through the port 120 with the chamber 90 for returning any unused fuel from the injector to the fuel tank that may escape upwardly past the plunger valve 87. Each of the levers 97, 98 and 99 may be provided with lateral projections or lugs 123 (Figure 3) positioned above the upper end 96 of the rod 91 so that the injector valve 87 will be held firmly in its closed position during the non-firing operation. In other words, should the end 96 of the rod 91 while in operation be moved out of central alignment with the lever 97, the projections 123 insure the injector valve 87 being held to its closed position when the lever 97 is depressed and the cylinder associated therewith is in its non-firing condition.

When the fuel pump 24 is associated with a single cylinder diesel engine, the lever 97, push rod 103 and their associated parts are dispensed with. As shown in Figure 11, the pump 24 is disclosed connected to a single cylinder 124 through a fuel supply pipe 125 that is connected to the valve fitting 27 of the pump in substantially the same manner as the pipe 39 previously described. The supply pipe 125 communicates with the injector casing 21 that is arranged to conduct the atomized fuel into the combustion chamber of the cylinder 124 so that the fuel may be delivered in variable quantities to the cylinder as automatically determined by the load on the engine, through the instrumentality of the position of the slideable wedge member 49 relative to the control pin 47. Thus, it will be seen that the pump 24 may be operatively associated with either a single or multi-cylinder diesel engine for controlling the quantity of fuel in accordance with the load imposed on the engine.

In operating the multi-cylinder engine as shown in Figure 1, it may be assumed that the wedge member 49 and its associated parts are in their closed or zero position and after a supply of fuel has been introduced into the combustion chamber 20, with the fuel pump 24 and its associated parts in the position as shown in

Figure 9, so that the check valves cut off the flow of fuel into and out of the pump. As the engine is started, the speed of the governor causes the wedge member 49 to be moved transversely relative to the pump a distance determined by the engine load. Simultaneously, the shaft 62 is rotated and as the arm 61 rides up on the adjacent cam 63, the arm 58 of the lever 59 moves away from the wall of the opening 57. The spring 75 moves the plunger 73 and control pin 47 to the left a distance determined by the point of engagement of the shoulder 52 with the inclined side 53 of the member 49. This outward movement of the plunger 73 relative to the chamber 34 by the expansion of the spring 75 creates a suction in the chamber 34 which raises the valve 31 and allows oil to be introduced into the chamber 34 so as to fill the same. The openings 74 in the guide member 78 allow the oil to be uniformly distributed throughout the chamber 34. At the same time, assuming that the piston in the cylinder 15 is moved to its firing position, the shaft 66 will move the cam 112 to the position as shown in Figure 1, thus raising the lever 97 so that the pressure of the fuel into the chamber 85 (Figure 15) may raise the plunger 87 so as to move the valve 86 away from its seat 85 in order that the proper amount of atomized fuel may be delivered into the combustion chamber 20. During this operation, the cams 112 associated with the cylinders 16 and 17 are out of contact with their associated push rods 103 (Figures 6 and 7) so that the springs 113 of these cylinders act to move the lever 98 and 99 respectively, downwardly against the top of each rod 91 to force its associated valve 86 against its seat 85. Conversely, when the lower arm 61 of the lever 59 rides past the adjacent cam 63, the pressure of the spring 70 will move the upper arm 58 of the lever 59 against the wall of the opening 69 and the quick return movement of the plunger 73 into the chamber 34 that is now filled with oil, will force the fuel in the chamber 34 upwardly past the outlet check valve 38 so that the fuel may be uniformly distributed through the pipe 41, 42 and 43 to their associated cylinders and in such selected quantities as determined by the speed of the governor 54. Figures 12, 13 and 14 illustrate the different positions assumed by the wedge member 49 and its associated parts when the plunger 73 is moved from its closed or zero position (Figure 8) to its extreme or full load position. In Figure 12 the wedge member 49 is shown with its widest portion engaging the shoulder 52 so that both check valves are closed. In Figure 13 the wedge member 49 is moved transversely relative to the pump by the governor 54 so that an intermediate portion of the tapered side 53 engages the shoulder 52 and the end of the control rod 47 projects slightly into the opening 57 so that the parts are in their half loaded positions. In Figure 14 the wedge member 49 is moved transversely to its extreme position and the outer end portion of the tapered side 53 is in contact with the shoulder 52. The parts are now in their full load position with the end of the control pin 47 extending an appreciable distance within the opening 57. Thus, it will be seen that simple, efficient and positive means are provided for delivering variable quantities of fuel to one or more cylinders of a diesel engine as determined by the setting of the wedge member 49 which is under the operative control of the engine or governor 54 in order that the charge will be uniformly distributed to each of

the cylinders in accordance with the load imposed on the engine. The cams 63 on the shaft 62 control the operation of the pump 24 while the spaced cams 112 on the shaft 66 insure the proper injection valve to be opened during the firing operation and the other two valves to be firmly closed during the non-firing operation. The chamber 34 after each operation of the pump is filled with oil and the displacement of the plunger 73 determines the amount of fuel injected into the combustion chamber 20. The spring 70 which is much larger than the spring 75, is constructed and arranged so as to give a very rapid thrust to the plunger 73 so as to raise the valve 38 and force the oil in the chamber 34 into the combustion chamber, with the result that each droplet of oil enters the combustion chamber 20 very rapidly and every part of the surface of the droplet of oil is simultaneously attacked by the oxygen of the air in order to obtain complete combustion and minimum dissipation of the fuel. In other words, the oxygen of the air attacks the entire droplet of oil at practically the same instant so as to convert the largest possible amount of the droplet of oil into power, instead of being wasted as smoke or carbon. The purpose of the cam shaft 62 and the lever 59 is to force the spring 70 to its compressed position so that upon the sudden release and expansion of the spring, when the arm 61 of the lever 59 passes a cam on the shaft 62, the plunger 73 will be rapidly thrust into the chamber 34 in order to displace the oil therein and force the same through the supply pipe 39 into the combustion chamber 20. In other words, the cam shaft 62 and its associated parts have nothing to do with increasing or decreasing the pressure of the liquid in the chamber 34, since this is controlled by the rapidity and extent of movement of the plunger 73 into the chamber 34 under the influence of the spring 70 and the movement of the plunger 73 outwardly from the chamber 34 by the action of the spring 75. The distance the end portion of the plunger 73 projects into the chamber 34 is controlled by the position of the wedge member 49 and the oil displaced in the chamber 34 is in proportion to the size and cross sectional area of the plunger 73 that extends into the chamber 34.

The spring 70 provides the injecting force to insure the entire amount of fuel being introduced into the combustion chamber so that the fuel will burn instantly and completely, thus providing maximum power and practically no smoke and very little carbon formation. It will be seen that the spring injected feature provides very rapid injection and rapid burning of the fuel, as contrasted to cam actuated injection which pushes in the fuel slowly and causes incomplete combustion and leakage. Moreover, when the spring 70 is set at a certain pressure it will always remain practically the same or uniform, regardless of the speed of the engine.

The pump 24 and its associated parts may be associated with either a multi-cylinder engine such as shown in Figure 1 or with a single engine as shown in Figure 11 while the levers 97, 98 and 99 are only associated with a multi-cylinder engine for the purpose of insuring a proper and complete opening of the injector valves during the firing operation and the closing of the valves during their non-firing operation.

The rod or pin 91 constitutes a portion of the stem of the injector valve 87 that is engaged by the lever 97 and is forced by the pressure of the spring 113 to move and maintain the valve

against its seat at certain predetermined intervals during the operation of the engine. This push rod is forced upwardly by the action of its associated cam 112 at other predetermined intervals so as to insure proper and selected firing of each cylinder. The transverse movement of the wedge member 49 relative to the pump 24 insures the fuel being delivered to the engine, in a very small or microscopic quantity and is automatically changed in accordance with a change of the engine load.

Thus it will be seen that simple and efficient means are provided for rapidly injecting a select quantity of fuel into each cylinder, and that the fuel has time to gasify completely before it burns so that maximum consumption of the products of combustion are obtained with minimum loss of power or waste of the fuel in smoke.

It will be understood that the forms of the invention described are merely illustrative or preferred embodiments and that such changes may be made as fall within the purview of one skilled in the art without departing from the invention and the scope of the claims.

I claim:

1. A pump of the class described including a casing having a fuel chamber, an inlet check valve controlling the flow of fuel into the chamber, an outlet check valve for controlling the flow of fuel from the chamber, a reciprocating plunger extending into said chamber between the inlet and outlet check valve for creating suction and pressure to open selectively said check valves, expansible spring means on one side of the pump for moving the plunger into the chamber, a movable control pin in axial engagement with said plunger, a transversely disposed movable member having a tapered side slidably connected to said control pin for regulating the axial movement thereof, a pivoted lever having an upper and lower arm, the upper arm of said lever extending into the pump between the spring means and the control pin, means for moving said lever so as to compress said spring and for suddenly releasing the spring pressure so as to rapidly thrust the plunger into the chamber to force the fuel therein past the outlet check valve, and yieldable means within said chamber and disposed opposite to said spring means for moving the plunger outwardly therefrom, said plunger in its outward movement creating a suction in the chamber for drawing fuel past the inlet check valve and into the chamber to fill the same.

2. A pump of the class described including a fitting connected to one end of the pump, said fitting having a fuel chamber, an inlet check

valve controlling the flow of fuel into the chamber, an outlet check valve for controlling the flow of fuel from the chamber, a reciprocating plunger mounted in the fitting and extending into said chamber for creating suction and pressure to open selectively said check valves, said pump on its opposite end having a tubular housing, an expansible spring mounted in said housing, a control pin axially slideable in said pump and engaging at one end said plunger, said pump having a transverse opening, said pin having a transverse recess registering with said transverse opening, a movable member slidably mounted in said recess and extending through said transverse opening, said movable member having a tapered side arranged to engage the adjacent wall of said recess for controlling the axial movement of said control pin, a pivoted lever having an upper and lower arm, the upper arm of said lever extending into the pump between said housing and said control pin and engaging the latter, means connecting said upper arm to said expansible spring, means for moving said lever so as to compress said spring and for suddenly releasing the spring so as to rapidly thrust the plunger into the chamber to force the fuel therein past the outlet check valve, and yieldable means within said chamber and engaging said plunger for moving the latter outwardly, said plunger in its outward movement creating a suction in the chamber for drawing fuel past the inlet check valve and into the chamber to fill the same.
